UNITED STATES PATENT OFFICE

FREDERICK J. OSIUS, OF MIAMI, FLORIDA

DESIGN FOR AN ELECTRIC COOKER

Application filed June 4, 1932. Serial No. 43,975. Term of patent 3½ years.

To all whom it may concern:

Be it known that I, FREDERICK J. OSIUS, a citizen of the United States, residing at Miami, in the county of Dade and State of Florida, have invented a new, original, and ornamental Design for an Electric Cooker, of which the following is a specification, reference being had to the accompanying drawing, forming part thereof, in which:—

Fig. 1 is a side elevation of the electric cooker showing my new design, and

Fig. 2 is a top plan view.

I claim:

The ornamental design for an electric cooker as shown.

FREDERICK J. OSIUS.
